US0D1016781S

(12) **United States Design Patent** (10) Patent No.: **US D1,016,781 S**
(45) Date of Patent: ** Mar. 5, 2024

(54) **BONE CONDUCTION HEADPHONES**

(71) Applicant: **Zhonghua Tan**, Huizhou (CN)

(72) Inventor: **Zhonghua Tan**, Huizhou (CN)

(**) Term: **15 Years**

(21) Appl. No.: **29/859,913**

(22) Filed: **Nov. 15, 2022**

(51) LOC (14) Cl. **14-01**

(52) U.S. Cl.

USPC **D14/205**

(57) **CLAIM**

The ornamental design for bone conduction headphones, as shown and described.

DESCRIPTION

FIG. 1 is a perspective view of bone conduction headphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the bone conduction headphones that form no part of the claimed design.

1 Claim, 8 Drawing Sheets
